UNITED STATES PATENT OFFICE.

FRANK. J. CASE AND JAMES F. PRESTON, OF ARRINGTON, KANSAS.

CAR-COUPLING.

SPECIFICATION forming part of Letters Patent No. 401,329, dated April 16, 1889.

Application filed June 30, 1888. Serial No. 278,616. (No model.)

To all whom it may concern:

Be it known that we, FRANK. J. CASE and JAMES F. PRESTON, citizens of the United States, residing at Arrington, in the county of Atchison and State of Kansas, have invented 5 new and useful Improvements in Car-Couplings, of which the following is a specification.

The invention relates to improvements in car-couplers; and it consists in the construction and novel combination of parts herein-after described, illustrated in the accompanying drawings, and pointed out in the appended claims.

15 In the drawings, Figure 1 is a perspective view of the end of a car having a coupler embodying the invention attached. Fig. 2 is a central vertical longitudinal section of the draw-heads thereof. Fig. 3 is a plan view of 20 one of the said draw-heads. Fig. 4 is a perspective view of the link-bar disconnected from the draw-head.

Referring to the drawings by letter, A designates the end of a car having the draw-bar 25 a, to which the draw-head B is connected in any suitable manner. The said draw-head has the edges of its mouth converging inwardly, as shown, and is provided in its roof and floor with the registering longitudinal 30 slots C C', respectively.

D is a transverse shaft journaled in one of the draw-heads B, just below the roof and at the front end of the upper slot, C, which shaft is provided with the central lever arm or 35 crank, d, within the draw-head and the crank-handles d' outside of its bearings. The opposite draw-head has the bearings for the corresponding shaft D open at top, so that the said shaft can be lifted out of position, if 40 desirable or necessary.

E is the link or coupling bar, having the vertical notches e at equal distances from its ends, which notches have rectangular shoulders e' at their outer sides and rounded 45 shoulders e'' at their inner sides. The lower edge of the link-bar outside of the said notches inclines upward therefrom, as shown at e'', Fig. 4. The inclined end e''' of the link-bar rides up the inclined floor of the mouth 50 of the draw-head, and the adjacent notch e catches over the shoulder F, formed within said mouth where the latter merges into the recess of the draw-head.

G is a transverse rectangular engaging- 55 frame seated in a vertical transverse recess,

g, in the draw-head, descending from the forward end of the slot C in front of the shaft D.

H is a cord or wire having its lower end secured in the eye h on the upper edge of said frame and ascending thence through suitable 60 guides to the top of the car.

When the end of the link-bar enters the draw-head, it lifts the said frame, and after the notch e catches over the shoulder F the frame falls in its seat and its upper transverse 65 bar engages on the top of the link-bar and holds the latter down on said shoulder. When the link-bar has entered the draw-head, the lever-arm or crank d lies upon its upper surface, and by means of the crank-handles d' 70 the said arm can be depressed upon the entered end of the link-bar, and the opposite free end can be inclined upward to couple with a higher draw-head.

If desired, the wire or cord H may have 75 lateral extensions passing over pulleys, so that the frame G may thereby be lifted from the side of the car and the link-bar released therefrom, as well as by drawing said wire upward from the top of the car. 80

Having described our invention, we claim—

1. The combination of the draw-head having the shoulder F and the recess g, the link engaging the shoulder F, and the frame G, seated in the recess g and having its upper 85 cross-bar bearing on the upper edge of the link, the said frame G being arranged entirely within the draw-head, as set forth.

2. The combination of the draw-head having a shoulder, F, the link engaging said 90 shoulder, the frame G, arranged within the draw-head and engaging the link, and the shaft D, mounted in the draw-head in rear of said frame G and having its crank-arm d resting on the upper edge of the link, as spec- 95 ified.

3. In a car-coupler, the combination of the recessed draw-head provided with the slots C C', the link-bar E, and the transverse shaft D, provided with the central lever-arm, d, and 100 crank-handles d' outside of its bearings.

In testimony that we claim the foregoing as our own we have hereto affixed our signatures in presence of two witnesses.

FRANK. J. CASE.
JAMES F. PRESTON.
